UNITED STATES PATENT OFFICE

CHARLES HENRY CORRIGAN, OF PHOENIX, ARIZONA

COMBINED CIGAR AND CIGARETTE EXTINGUISHER

Application filed January 9, 1929. Serial No. 331,183.

The present invention relates to improvements in tobacco users' appliances and has reference more particularly to a device for quenching or extinguishing a lighted cigar or cigarette in a simple and efficient manner.

One of the important objects of the present invention is to provide a device of the above mentioned character that may be detachably associated either with a match case or the closed end of a cigarette lighter, said device being of such size as to occupy a very small amount of space when placed in the pocket of the user so that the device is at all times at hand for use.

15 A further object is to provide a device of the above mentioned character that includes a water receptacle having a well extending downwardly therein, the bottom of the well being open and arranged within the open bottom portion of the well is a sponge, a spring pressed cap being arranged within the water receptacle for normally closing the lower open end of the well to prevent the entrance of water to the sponge, a hinged cap or 20 lid being provided for the open upper end of the well which lid can be readily and easily swung to an open position to permit the insertion of the lighted end of a cigar or cigarette when it is desired to extinguish the same.

25 A further object is to provide a device of the above mentioned character that is simple in construction, inexpensive, strong and durable and further well adapted to the purpose for which it is designed.

Other objects and advantages of the invention will become apparent from the following description when taken in connection with the accompanying drawing.

40 In the accompanying drawing wherein like reference characters indicate corresponding parts throughout the same:

Figure 1 is a top plan view of the device embodying my invention showing the same attached on one end of a cigarette case.

45 Figure 2 is a sectional view taken approximately on the line 2-2 of Figure 1.

Figure 3 is a longitudinal sectional view taken on the line 3-3 of Figure 1, and

50 Figure 4 is a fragmentary detail perspec-

tive view of the inner end of the water container showing the attaching means associated therewith.

In the drawing wherein for the purpose of illustration is shown the preferred embodiment of my invention, the numeral 1 designates a substantially rectangular shaped water container, the outer end of which terminates in the conical portion 2, and a filling neck 3 is formed at the smaller end of the conical portion 2. A cap 4 is detachably secured on the filling neck 3 for normally closing the same.

A split attaching flange 5 extends from the closed inner end of the container 1, and this split flange is adapted to encircle one end of a match case or the closed end of a cigarette lighter, as suggested in Figure 1. A clamping band such as is shown at 6 extends around the split flange for clamping the same on the end of the match case or cigar lighter to prevent the accidental disengagement of the container from the article on which it is secured.

The top of the container 1 is formed with an opening through which extends the conical well 7, the lower end thereof being open and terminating at the intermediate portion of the container. The upper edge of the well is flanged for disposition on the top of the container around the opening formed therein, and any appropriate means may be provided for fixedly securing the well in position in the water container.

A sponge 8 is placed in the lower end of the well and the water is normally prevented from contact with the sponge through the medium of the cup-shaped member 9 that encircles the lower end of the well and a rubber disc 10 is arranged in the bottom of the cup shaped member to engage with the lower edge of the well 7.

An expandable coil spring 11 is arranged with the water container 1 for disposition between the bottom of the container and the cup shaped member 9 for normally urging the same upwardly to maintain the rubber disc 10 in contact with the lower edge of the well, thus sealing the lower end of the well.

55 60 65 70 75 80 85 90 95 100 A hinged lid 12 is provided for the upper

open end of the well 7, and an axial coil spring 13 is associated with the hinged lid for normally maintaining the same in a closed position, as clearly shown in Figures 5 2 and 3.

In the use of the device, the lighted cigar or cigarette is inserted into the well 7 after the lid 12 has been raised, and a downward pressure is placed upon a sponge 8 by the 10 lighted end of the cigar or cigarette, and this pressure will result in the cup-shaped member 9 being forced downwardly against the tension of the coil spring 11 so that the rubber disc 10 is moved away from the lower 15 edge of the well 7 and water is permitted to saturate the sponge and the dampened sponge will extinguish or quench the lighted end of the cigar or cigarette in a positive and efficient manner. As soon as the cigarette or 20 cigar is removed from the well the spring 11 automatically returns the cup shaped member 9 and the rubber disc 10 arranged in the bottom thereof into its normal position, closing the open lower end of the well and preventing water from coming in contact with 25 the sponge.

It will thus be seen from the foregoing description that I have provided a device of the above mentioned character that can be 30 carried around on the person and will not occupy any considerable amount of space. Furthermore, a device of this character will at all times be positive and efficient in carrying out the purposes for which it is designed, 35 and due to its simplicity, the same can be constructed and sold at a very low cost.

If desired, the extinguisher can also be used 40 as an adjunct on ash trays and stands.

While I have shown the preferred embodiment of my invention it is to be understood 45 that minor changes in the size, shape and arrangement of parts may be resorted to without departing from the spirit of the invention and the scope of the appended claims.

Having thus described the invention, what 50 I claim as new and desire to secure by Letters Patent is:—

1. In a cigar or cigarette extinguisher of 55 the class described, a water receptacle provided with a filling opening, a closure therefor, the top of the receptacle being formed with an opening, an open ended well extending downwardly through the opening, the lower end thereof being spaced from the bottom of the water receptacle, an absorbent member being arranged in the well, a spring 60 pressed closure for the open lower end of the well to normally prevent water in the container from reaching the absorbent member, said spring 65 pressed closure being moved to an operative position to permit the absorbent member to become saturated when a downward pressure is exerted on the absorbent member by the cigar or cigarette to

be extinguished, and a lid providing a closure for the upper open end of the well.

2. In a cigar or cigarette extinguisher of the class described, a water receptacle provided with a filling opening, a closure therefor, the top of the receptacle being formed with an opening, an open ended well extending downwardly through the opening, the lower end thereof being spaced from the bottom of the water receptacle, an absorbent member being arranged in the well, a spring 70 pressed closure for the open lower end of the well to normally prevent water in the container from reaching the absorbent member, said spring 75 pressed closure being moved to an operative position to permit the absorbent member to become saturated when a downward pressure is exerted on the absorbent member by the cigar or cigarette to be extinguished, a lid providing a closure for the 80 upper open end of the well, said spring 85 pressed closure including a cup shaped member encircling the lower end of the well, a rubber disc arranged in the bottom of the cup-shaped member for engagement with the 90 lower edge of the well, and an expansible coil spring arranged between the bottom of the container and the cup shaped member.

3. In a cigar or cigarette extinguisher of the class described, a water receptacle provided with a filling opening, a closure therefor, the top of the receptacle being formed with an opening, an open ended well extending downwardly through the opening, the lower end thereof being spaced from the bottom of the water receptacle, an absorbent member being arranged in the well, a spring 95 pressed closure for the open lower end of the well to normally prevent water in the container from reaching the absorbent member, said spring 100 pressed closure being moved to an operative position to permit the absorbent member to become saturated when a downward pressure is exerted on the absorbent member by the cigar or cigarette to be extinguished, a lid providing a closure for the 105 upper open end of the well, means at one end of the container for attaching the same to a support.

4. In a cigar or cigarette extinguisher of the class described, a water receptacle provided with a filling opening, a closure therefor, the top of the receptacle being formed with an opening, the lower end thereof being spaced from the bottom of the water receptacle, an absorbent member being arranged in the well, a spring 115 pressed closure for the open lower end of the well to normally prevent water in the container from reaching the absorbent member, said spring 120 125 pressed closure being moved to an operative position to permit the absorbent member to become saturated when a downward pressure is exerted on the absorbent member by the cigar or cigarette to be extinguished, a lid 130

providing a closure for the upper open end of the well, means at one end of the container for attaching the same to a support, said means comprising a split flange for encircling the support, and a clamping band extending around the flange.

5 In testimony whereof I affix my signature.
CHARLES HENRY CORRIGAN.
